DESIGN FOR A CLOCK CASE

Charles H. Granger, Waterbury, Conn., assignor to The Waterbury Clock Company, Waterbury,
Conn., a corporation of Connecticut

Application February 10, 1937, Serial No. 67,557

Term of patent 3½ years

To all whom it may concern:

Be it known that I, Charles H. Granger, a citizen of the United States, residing at Waterbury, in the county of New Haven and State of Connecticut, have invented a new, original, and ornamental Design for a Clock Case, of which the following is a specification, reference being had to the accompanying drawing, forming part thereof.

Fig. 1 is a perspective view of a clock case showing my new design; and

Fig. 2 is an edge view of the same.

I claim:

The ornamental design for a clock case substantially as shown.

CHARLES H. GRANGER.
